UNITED STATES PATENT OFFICE.

CHARLES F. KETTERING, OF DAYTON, OHIO, ASSIGNOR TO GENERAL MOTORS RESEARCH CORPORATION, OF DAYTON, OHIO, A CORPORATION OF DELAWARE.

BINDING ELEMENT.

Application filed January 6, 1921. Serial No. 435,417.

To all whom it may concern:

Be it known that I, CHARLES F. KETTERING, a citizen of the United States of America, residing at Dayton, county of Montgomery, and State of Ohio, have invented 5 certain new and useful Improvements in Binding Elements, of which the following is a full, clear, and exact description.

The present invention relates to means 10 for binding together an assembly of elements preparatory to heating in an induction furnace and in its preferred form of embodiment relates particularly to a form of binding wire for holding in proper relation, copper cooling fins and internal-combustion engine cylinders preparatory to brazing the cooling fins to the cylinder in the process described in my U. S. Patent No. 1,453,858, dated May 1, 1923, on process 15 of joining metals.

In furnaces of the induction type, as is well known, when conducting materials are subjected to the influence of the magnetic field generated by current flowing in the 20 primary winding of such furnaces, currents are induced in the objects to be heated and heating results from the resistance of these objects to the passage of such induced current. In certain forms of furnaces, the 25 induced currents are circuits set up in properly placed materials to be heated and in other forms these induced currents are eddy currents.

In the prior application, there is described 30 specifically a process of brazing non-ferrous, specifically copper, cooling elements to ferrous metal cylinders by assembling the cooling elements and cylinders, fastening the assembly together by use of 35 an iron wire and heating the assembly by heat generated in the assembly itself.

In that process it was found necessary to heat insulate the binding wires from the assembly and also to electrically insulate the 40 ends of the wires from each other so as to break the circuit formed by the ring of wire around the assembly.

The present application relates specifically to a form of binding wire especially 45 adapted for this last described operation.

The objects of the invention include the production of a wire of the proper length which does not need to have insulating material twisted between its ends to break the 50 circuit. Also a binding wire of the type

just mentioned which shall be easily and economically prepared and quickly put in place.

Further objects and advantages of the present invention will be apparent from the following description, reference being had to the accompanying drawing, wherein a preferred form of embodiment of the invention is clearly shown.

In the drawing:

Fig. 1 represents an assembly of cylinder, cooling fins, and binding wire showing clearly the use of the wire.

Fig. 2 is an enlarged detail view showing a plan of the insulating plate.

Fig. 3 is a side view of the plate shown in Fig. 2.

In the drawing, 10 indicates an internal-combustion engine cylinder upon which is assembled a series of cooling fins 11, which fins are fastened in their proper relative position to the cylinder by means of wires 12, insulated from the fins by means of a suitable material, preferably asbestos, indicated at 13.

The binding wires 12 are made up in the present instance of two pieces of iron wire of suitable size, one end of each piece being inserted through the eye, 20 of insulating plate 21.

This insulating plate is preferably of sheet metal covered with an insulating glaze and will be ordinarily of the form indicated in Figs. 2 and 3 so as to make it conform to the contour of the assembly.

It will, of course, be obvious that plates 21 intended for use with assemblies other than cylinders and the like, as indicated in Fig. 1, may be of a suitable form to conform to the contours of such assemblies.

In the use of this particular binding wire, the two pieces of iron wire properly attached to the plate form a continuous piece which is placed around the assembly and the free ends twisted as indicated at 30 in order to hold the assembly firmly together.

Further description of the operation is not considered necessary as it appears to be obvious from the description and illustration.

It will, of course, be understood that the insulating piece 21 may be made of any suitable material, although glazed metal is considered preferable.

While the form of mechanism herein

shown and described, constitutes a preferred form of embodiment of the present invention, it is to be understood that other forms might be adopted all coming within the scope of the claims which follow.

What I claim is as follows:

1. A means for binding together assemblies of elements for treatment in induction furnaces, comprising a plurality of pieces 10 of conducting material attached together by means of electrically insulating material.
2. A means for binding together assemblies of elements for treatment in induction furnaces, comprising a plurality of pieces 15 of wire fastened together to form a continuous piece by means of electrically insulating material.
3. A means for binding together assemblies of elements for treatment in induction 20 furnaces, comprising two pieces of wire at-

tached to a section of electrically insulating material so as to form in effect a single piece.

4. A means for binding together assemblies of elements for treatment in induction 25 furnaces, comprising two pieces of wire connected by means of a metal plate which latter is covered with an electrically insulating glaze.

5. As a new article of manufacture a 30 metal plate in the form of a short strip having holes adjacent its ends and being entirely covered with an electrically insulating glaze.

In testimony whereof I hereto affix my 35 signature.

CHARLES F. KETTERING.
